MACHINE FOR PRINTING ON SHEETS INCLUDING EXPANSIBLE SHEETS SUCH AS TEXTILES
Jacques Lucien Vechot, Lyon, Rhône, France, assignor to
Société Alsacienne de Constructions Mécaniques, Haut-Rhin, France, a company of France
Filed Nov. 30, 1961, Ser. No. 156,012
Claims priority, application France Dec. 7, 1960
5 Claims. (Cl. 101—212)

This invention relates to printing machines and more especially though not exclusively to machines for printing patterns on flexible sheet materials having substantial extensibility, such as textile fabrics and the like. The invention is also applicable however to the printing on materials of other character, including paper, plastics, sheet metal, and the like.

Great difficulties have been encountered heretofore when it has been attempted to use rotary printing machines, e.g. offset machines, for the printing of patterns on extensible sheet materials such as fabrics. A chief difficulty has been due to the requirement for extreme accuracy in the developed length of the printing cylinders and rolls and in the maintaining of such length to the prescribed value during long periods of work. This has considerably increased the cost of machine construction and maintenance, and has required frequent replacement of the printing rolls, so that operating costs were prohibitive. The true source of the trouble lies of course in the lack of dimensional stability of fabrics in contrast to paper and other inextensible sheet materials.

It is an object of this invention to provide an improved printing machine which will be free of these difficulties and will enable perfect printing of any desired patterns, in one or more colours, to be performed on sheet materials of any reasonable character, including materials having substantial dimensional instability in one or more dimensions, such as textile fabrics.

In accordance with a basic aspect of the invention there is provided a printing machine comprising means for supporting a length of sheet material; means for intermittently advancing the supporting means in a longitudinal direction; a printing roll supported with its axis parallel to said longitudinal direction, means providing an ink pattern around the periphery of the roll, and means operable in timed relationship with the advancing means for moving the roll transversely across the surface of the material in substantially frictionless rolling engagement therewith during a stationary period of said material supporting means to transfer the pattern to the material.

The pattern providing means may comprise a plate positioned to one side of said sheet material and in the same general plane as it, the printing roll being adapted to take up ink from said plate and transfer it to said material in accordance with a selected pattern, means being provided for supplying ink to the plate in timed relationship with the general operation of the machine.

The supporting means may comprise an endless conveyor belt or the like. The means for intermittently advancing the conveyor preferably comprise a plurality of longitudinally reciprocable clamping units spaced along the conveyor and engageable for gripping the conveyor and the sheet thereon across the full width of the sheet, and actuator means cyclically operated for sequentially engaging the clamp units, advancing the clamp units in a longitudinal direction and then disengaging the clamp units and moving them back to their initial position. Preferably, at least one stationary clamp unit is further provided engageable for gripping the conveyor and material across the full width thereof after the conveyor has been advanced one step and disengageable for releas-

2

ing the conveyor and material prior to a further step of advance.

With the machine of the invention, highly accurate printing operations can be performed, the degree of accuracy being primarily determined by the precision achieved in the successive steps of advance of the material, which latter can be effected with a very high degree of precision.

10 The above and further objects, features and advantages of the invention will appear as the disclosure proceeds, with reference to the accompanying drawings which illustrate a preferred form of embodiment given by way of example but not of limitation.

15 FIG. 1 is a schematic perspective view illustrating the basic principle of the machine.

FIG. 2 is an elevational view of one practical embodiment of a polychrome, dry offset printing machine constructed according to the invention;

20 FIG. 3 is a corresponding view in plan;

FIG. 4 is an elevational view of the intermittent conveyor advancing means;

FIG. 5 is a corresponding view in plan;

FIG. 6 is a larger-scale view in section on line VI—VI of FIG. 4.

25 FIG. 7 is a sectional view, on a further increased scale, on line VII—VII of FIG. 4.

FIG. 8 is an enlarged sectional view on line VIII—VIII of FIG. 3.

30 FIG. 9 is a corresponding plan view.

FIG. 10 is a section on line X—X of FIG. 9.

FIG. 11 is a view in section on an enlarged scale, on the line XI—XI of FIG. 3, or on line XI—XI of FIG. 12.

FIG. 12 is a plan view corresponding to FIG. 11.

35 FIG. 13 is a section on line XIII—XIII of FIG. 12.

FIGS. 14a, 14b and 14c are simplified partial views illustrating the operation of the printing roll carriage; and

FIG. 15 is a schematic view of the central sequencing control of the machine.

Referring to the simplified view of FIG. 1, an improved offset printing machine comprises a support in the form of an endless conveyor band 1 of flexible substantially inextensible material trained about end drums 11 and 12 and provided with means, not shown, for advancing the conveyor stepwise in a longitudinal direction as shown by arrow f1.

40 The band 1 may be natural or synthetic rubber provided with reinforcement of natural or synthetic fibers, glass wire or the like for rendering the conveyor band substantially inextensible. Alternatively the support may be provided in the form of a plurality of parallel endless chains or belts. The sheet of material to be printed on is shown at 10 and is secured to the outer surface of the conveyor by any suitable means, such as adhesive, or by means of clamps, or pins spaced along the length of the conveyor and projecting from its outer surface.

45 The machine further includes a set of wetting rolls 3, a set of inking rolls 2, a pattern plate or block 4 supported on a bedplate 5, and a rotary blanket or printing roll 6.

The wetting and inking rolls and the pattern plate are 50 mounted to one side of the support assembly described, and the rolls are arranged for displacement parallel to the direction f1 so as to engage the upper surface of the pattern plate. The printing roll 6 is mounted for displacement transverse to the direction f1.

55 In operation, in a first stage of the operating cycle the conveyor 1 is advanced one step in the direction f1, while at the same time the wetting rolls 3 and inking rolls 2 are displaced in the same direction on to and over the surface of the plate 4 so as to apply ink to said surface.

60 During such displacement the printing roll 6 is positioned above the upper leaf of the conveyor 1 and out of engagement with the surface of web 10 attached thereto.

In a succeeding stage of the cycle, the inking and wetting rolls having performed their function are returned to their initial positions as shown, while the blanker or printing roll 6 is rolled across the surface of the pattern plate 4 so as to take up ink deposited on the prominent areas of the plate.

In the next stage the printing roll 6 is displaced transversely to roll across the surface of the sheet 10 in the transverse direction thereby to transfer to said surface the ink pattern taken up by it from the pattern plate. The cycle described is repeated step by step each step of advance of the conveyor may correspond in length to the longitudinal dimension of the pattern on the pattern plate. It will be noted that the accuracy of the transfer or printing action is determined almost exclusively by the accuracy of the step-by-step advance of the conveyor.

While the arrangement schematically described above referred more especially to the form of offset printing process in which the pattern plate is first wetted then inked so as to transfer ink to the prominent areas of the plate, it is equally applicable to intaglio offset processes in which ink is deposited on to the plate and then wiped off with scraper means from the prominent areas so as to transfer the recessed pattern from the plate on to the sheet of material. Further, the same principle can be applied to the so-called dry offset process, in which case only the inking rolls 2 would be used. Moreover, in applying the invention to multi-colour printing processes, it would simply be necessary to provide a number of similar printing assemblies each of which may be similar to that schematically shown in FIG. 1, and spaced longitudinally along the sheet, with all the printing assemblies being operated in synchronism. Correct register is easily achieved if the pattern plates are correctly positioned on the bedplates and the step-by-step advance of the conveyor is accurately adjusted.

A practical embodiment of a polychrome, dry offset printing machine based on the principle of the invention presented above will now be described in detail with reference to FIGS. 2-15, in which components corresponding to components shown in FIG. 1 are designated with the same references as in that figure.

Referring first to FIGS. 2 and 3, there is shown an endless supporting conveyor belt 1 to the outer side of which is affixed the sheet of flexible material 10 to be printed on, and which belt is trained around the end drums 11 and 12. The drums are journaled on shafts 14 and 15 mounted in opposite ends of a machine frame 16. The embodiments described related to a polychrome printing process involving black and three colours, and hence comprises four similar printing assemblies 21, 22, 23 and 24 spaced along the length of the conveyor. For imparting intermittent step-by-step advance to the conveyor in the longitudinal direction shown, by arrow f1 there is provided stepping mechanism including four clamping trucks 26, 27, 28, 29 (see FIGS. 4 and 5) spaced longitudinally of the conveyor and each adapted to be reciprocated a limited distance over a corresponding length of longitudinal track 31, 32, 33, 34. Each clamping truck is provided with clamping means adapted to engage a related area of the side edge of the upper leaf of the belt 1 as will be presently described in detail. All four trucks are reciprocated in unison over their respective tracks; for this purpose a foremost one 26 of the trucks is connected by a connecting rod 35 with a piston reciprocating in a double-acting fluid pressure actuator V1, while all four trucks are interconnected by intervening connecting rods 37, 38, 39 so as to be driven in unison. The reciprocatory stroke is determined by engagement of a stop 41 projecting from the bottom of truck 26 with each of two longitudinally spaced abutments 42 and 43 preferably made adjustable relatively to the frame 16.

The four trucks are similarly constructed, each comprising a generally rectangular body 46 (FIG. 6) having four flanged rollers 47 journaled to its under surface for en-

gagement with the rails forming the aforementioned track 31. The flat upper surface of the body 46 of each truck serves as a lower clamping surface for engaging the under side of the belt 1, and cooperates with an upper clamping member 48 supported on the truck by way of vertical rods slideable in a pair of vertically disposed double-acting hydraulic cylinders V2 arranged at opposite sides of the plate 46 as clearly shown in FIG. 6. As there shown, a line 51 is connected with the lower ends of both actuators V2 and a line 52 is connected with the upper ends of both actuators; valve means, not shown, are provided for alternately connecting line 51 to the pressure source and line 52 to exhaust for raising the upper clamping member 48 to release the belt 1, and connecting line 52 to the source and line 51 to exhaust to clamp the belt 1. The operation of the stepping mechanism described is briefly as follows:

With the clamping trucks in the positions shown in FIGS. 4 and 5, pressure oil is supplied to the actuators V2 of all the trucks through line 52 to lower the tops 48 thereby to clamp the upper leaf of belt 1 (and sheet material 10 affixed to it) at four spaced points along the length of the belt. Simultaneously or a short time later pressure oil is applied to a line 54 (FIG. 4) connected with the rear end of stepper actuator V1 whereby all four trucks are displaced forward until abutment of stop 41 with the front abutting surface 43, carrying the conveyor belt forward in their displacement. The pressure oil valving is then reversed so as to connect line 51 of each actuator V2 with the pressure source to release the conveyor and connect line 55 of actuator V1 with the pressure source whereby all four trucks are returned to their rearmost positions with stop 41 abutting rear abutment surface 42 as shown in FIG. 4. During the return movement of the clamping trucks the belt 1 is released from the clamping means. However, more positively to prevent any tendency for the belt to be partially carried back by the trucks through friction, a stationary clamping unit is preferably provided, generally designated 56 in FIGS. 4 and 5 and shown in detail in FIG. 7. The stationary clamp 56 is very similar in structure to each of the movable clamps constituted by the trucks such as 26 except that its body 46a instead of being mounted on rollers is fixedly secured to the frame 16. The stationary clamp 56 comprises a vertically movable top member 48a supported on the piston rods of vertical actuators V3 (corresponding to actuators V2 of FIG. 6) which are connected at their lower ends with oil line 60 and at their upper ends with oil line 59. Oil lines 51 and 59 may be interconnected in common and lines 52 and 60 may be interconnected in common so that the stationary clamp is actuated to releasing condition when the movable clamps are actuated to clamping condition, and vice versa.

Each of the end drums 11 and 12 is rotatably mounted around the related stationary shaft 14 or 15 by way of a freewheel device 61 or 62 (FIG. 4) so as only to permit rotation of the drums in the sense that causes advance of the conveyor belt in direction f1 but prevents reverse rotation. Moreover, each end drum 11 and 12 is provided with electromagnetic brake means generally shown at 63, 64 (see FIG. 5). These are safety features serving to prevent any undesired motion of the belt at times when such motion might result in faulty printing or other defects.

The printing assemblies will now be described with especial reference to the assembly 21 (FIGS. 2 and 3). Each such printing assembly comprises a frame structure including a stand 65 (also see FIGS. 8, 9 and 10) for supporting the inking rolls, a stand 66 for supporting the bedplate 5 supporting a pattern plate or block, and a stand 67 for supporting the printing roll 6. The stand 67 comprises spaced upright members and a bridge structure supported thereby which extends transverse to the direction of the belt and over and across the upper surface

of the conveyor belt, so as to allow the printing roll 6 to be rolled across the surface of the work as later described in detail. The stands 65 and 66 are positioned to one side of the belt and their general arrangement will become apparent from the drawings as the disclosure proceeds. All three stands 65, 66 and 67 are fixedly related to the conveyor frame structure 16 as by being firmly imbedded on common foundations therewith.

The inking assembly supported on stand 65 is generally conventional in a dry offset process and will only be described in brief. Said assembly comprises a container 71 providing a store of ink and an associated roll 72 directly contacting a store of ink and an associated roll 72 directly contacting the ink in the container, a swinging ink-transfer roll 73, a foremost roll 74, an intermediate roll 75, a pair of stationary inking rolls 76 and 77, and three spreader rolls 78, 79, and 80. All the rolls except the swinging roll 73 are permanently rotated during operation of the machine by means presently described; moreover the three spreader rolls in addition to their rotation are axially reciprocated in the usual way for smoothly spreading the ink across the surface of the inking rolls.

The means for driving the rolls in rotation comprise an electric motor M mounted on the frame 65 and driving through reducer gearing not shown an output screw shaft formed with two threaded sections 83 and 84 of opposite pitch, respectively engaged by worm gears 85 and 86 secured coaxially with the rolls 72 and 74. The remaining rolls are driven off the roll 74 through a train of gears not shown, the primitive circumferences of which gears would coincide, in the drawing of FIG. 8, with the circumferences of the rolls since all the rolls must be so driven as to roll with respect to one another without relative circumferential slippage, and hence all the rolls must have equal peripheral linear velocities and revolve in opposite senses as from one roll to the roll next in the series. The drive gearing is housed in recesses formed in the uprights of the frame 65. To provide the aforementioned axial reciprocation of the spreader rolls 78, 79 and 80, there is used in the example herein described mechanism including a grooved ring 95 (FIG. 10) secured coaxially with the spreader roll 78, and engaged by driving fork 97 which is pivoted at a fixed point 98 to the stand 65 and having its end remote from that engaging the grooved ring 95, engaging a helical groove formed in the periphery of a cam 99. The cam 99 is secured to a gear 101 which meshes with a gear 102 which in turn engages a suitable one of the gears of the train serving to rotate the remaining rolls of the inking assembly as above described.

The relatively stationary inking assembly just described and including the stationary inking rolls 76 and 77 cooperates with a movable inking assembly or ink transfer assembly comprising three inking rolls 87, 88, 89 which are reciprocated as will soon be described to transfer ink from the stationary rolls 76, 77 to the surface of the pattern plate 4 supported on stand 66. For this purpose the transfer rolls 87, 88, 89 are journalled on a carriage 92 mounted on rollers 93 engaging the rails 94, 95 which are secured in part to the upper surface of stand 65 and in part to the upper surface of stand 66 (also see FIG. 10). The carriage 92 has side portions extending below the track 94-95 and having rollers 104, 105 journalled thereon which engage the under side of a pair of rails 94, 95 serving to prevent the carriage 92 from derailing. As shown, carriage 92 comprises a pair of side flanges 106, 107 of trapezoidal form held in parallel spaced relation by tubular spacers 108, 109.

Each movable inking roll or transfer roll 87, 88, 89 is supported from the carriage 92 so as to be vertically displaceable relatively to it a limited amount. Thus roll 87 is journalled at its ends between a pair of arms 111, 112 pivoted about horizontal pivots 113, 114 in the side

flanges of the carriage. Similarly each of the rolls 88 and 89 is journalled between the pair of arms 115-116 and 117-118 pivoted on the pivots 121-122 and 123-124 respectively. For reciprocating the transfer carriage 92 there is provided a reversible electric motor M1 supported from the stand 65 and carrying on its output shaft a drive pulley 125 connected by a V-belt 126 with a driven pulley 127 fixed on a transverse shaft 128 journalled in the stand 65 and carrying the pair of bevel gears 131, 132 on its respective ends. Meshing with these gears are bevel gears 133, 134 secured on longitudinally extending lead screws 135, 136 on which are engaged respective nuts 137, 138 secured to the outer sides of the respective side flanges 106 and 107 of the carriage 92. The lead screws 135, 136 have their one ends journalled in bearings 141, 142 secured to frame 65 and their other ends journalled in bearings 143, 144 secured to the frame or stand 66.

In operation, when motor M1 is rotated in one or the other direction, the lead screws 135, 136 are rotated through the transmission means described to traverse carriage 92 in a corresponding longitudinal direction relative to the frame. With carriage 92 positioned at the right hand extremity of its stroke according to FIGS. 8 and 9, the transfer rolls 87, 88, 89 are positioned in engagement with pattern plate 4, while at the other end of the displacement of the carriage the first two transfer rolls 87 and 88 are in engagement with the upper stationary inking roll 76 and the third roll 89 is resting upon the remaining upper stationary inking roll 77. Rotation is imparted to the movable inking rolls by their frictional engagement with the stationary inking rolls at the left hand end of their reciprocatory stroke, so that when said movable rolls reach the right hand end of their reciprocation in engagement with the pattern plate 4, they already possess a linear peripheral velocity which is substantially equal to the velocity required for a slip-free rolling engagement of said rolls with the surface of the pattern plate.

Now turning to the printing roll 6 (see FIGS. 2 and 3), this roll is supported on a carriage 146 (better shown in FIGS. 11 to 13) made up of a pair of spaced slide flanges 147, 148 interconnected by tubular spacers 151, 152, 153 and 154 and mounted on rollers 155, 156, 157 and 158 rolling on rails 161, 162 secured to the under surface of the corresponding stand 67, e.g. to the vertical webs of the horizontal channels comprising the frame members of said stand in the embodiment shown. The side flanges 147, 148 further carry lower rollers 163, 164 journalled on pivots 165, 167 and engaging the lower edges of the rails 161, 162 to prevent derailment of the upper rollers. The printing roll 6 is journalled at its ends in lever arms 168, 169 interconnected by a tubular spacer 171 and freely pivoted on pivots 172, 173 to the respective side flanges 147, 148. A double-acting hydraulic actuator V4 has one of its component members, e.g. the cylinder 170, attached to a support 174 carried by the upper spacer 154 of the carriage and its other component, the piston rod 175, connected to the spacer 171 so that on application of pressure fluid to a line 176 or a line 177 connected to the respective ends of the actuator the printing roll 6 will either be moved to the raised position shown in full lines in FIG. 11 or will be lowered to the chain-line position. In this latter position the roll 6 is in rolling engagement with the surface of printing plate 4 or with the surface of the work 10 supported on the belt 1, which in turn is supported on a table 178 (FIG. 11) secured to bridging stand 67.

For reciprocating the carriage 146 over its rails and rotating the roll 6 there is provided a reversible electric motor M2 supported on the carriage. A belt drive comprises a belt 181 trained around a pulley 179 mounted on the motor output shaft and a pulley 182 secured on a transverse shaft 183 journalled between the flanges 147, 148 of carriage 146. Shaft 183 also has secured to it near its opposite ends the gears 184 and 185 which mesh respectively with a pair of racks 186 and 187. These

racks are supported by and slideable relatively to the respective rails 161 and 162 for reasons later described. Longitudinal reciprocation of the racks relatively to the rails is effected through the respective double acting hydraulic actuators V5 (see FIG. 3) to the opposite ends of each of which pressure fluid is selectively applicable through lines 191 and 192. When motor M2 is energized to rotate in one or the opposite sense, the belt and gearing transmission means described operate to impart to the carriage 146 a displacement in a corresponding direction over the rails 161 and 162.

To improve the accuracy of the printing process and avoid the development of any torsional stresses in the printing roll 6, the roll 6 is positively rotated and for this purpose has a pair of gears 193 and 194 secured coaxially with it at its opposite ends, which mesh with respective gears 195 and 196 secured to the afore-mentioned pivot shafts 172 and 173. Said shafts further carry gears 197 and 198 which mesh with the afore-mentioned gears 184 and 185 respectively, engaging the racks 186 and 187.

The pitch diameters of the gears described are so determined with respect to one another that as the carriage 146 moves over the rails, the surface of printing roll 6 rollingly engages the surface of the pattern block 4 or the surface of the web 10, depending on the position of the roll, without any relative slippage and friction between the engaging surfaces. Since the gears 195 and 196 are coaxial with the shafts 172 and 173 serving as pivots for the arms 168 and 169 supporting the printing roll, it will be obvious that said gears remain constantly in mesh with the gears 193 and 194 secured to the opposite ends of said rolls, regardless of the angular position of the rolls, so that the setting of the roll with respect to the racks is at all times retained at a strictly constant value. Since it is essential that the teeth of the gears 193 and 194 should be positively prevented from contacting the pattern block or the surface of the work at any time, the outer diameters of the gears 193 and 194 must be made smaller than the outer diameter of the printing roll 6. This makes it impossible to provide an arrangement wherein said gears would be in direct rolling engagement with the racks, since in order that such rolling engagement should be slip-free, the pitch radii of the gears would then have to be made equal to the outer radius of the printing roll and the outer tips of the gear teeth would then project beyond the periphery of the roll.

It will be appreciated that the arrangement described above has the advantage of achieving a positive, slipfree rolling of the printing roll upon its rails while preventing such unacceptable projection of gear teeth.

In the operation of the machine, the motor M is permanently driven to impart continuous rotation to the stationary inking rolls 76 and 77, and related components. The remaining movable components of the machine are operated in timed relationship in accordance with an automatic sequencing programme, by timed actuation of the hydraulic actuators and electric motors described, so as to accomplish the desired operating cycle. This phase of the invention will now be described with reference to an exemplary embodiment.

As shown in FIG. 15, the sequencing control for the various components is derived from a common camshaft 211 which is permanently driven in rotation from an electric motor M3 by way of a variable speed device generally designated 212 and a worm-and-wormgear reducer 213. Secured in spaced relation on the camshaft is a first set of cams, herein five, 221 through 225, which are engaged by actuator plungers protruding from respective hydraulic control valves generally designated D1 through D5. Each valve has a pressure inlet and a pressure outlet connection, and a pair of motor connections. All five pressure intake connections are connected to a common pressure line 241 connected with the outlet of a pump 242 (e.g. gear pump) drawing hydraulic liquid from a sump 243, and all five outlet connections are connected in parallel

to a common outlet line 244 delivering into the sump. The motor connections of each of the D valves are connected to the respective ends of a related one of the double-acting hydraulic actuator cylinders described earlier.

Specifically, the motor connections 54 and 55 of valve D1 are connected with the opposite ends of actuator V1 controlling the intermittent advance of the conveyor belt 1. Lines 51 and 52 from valve D2 connect with the ends of each of the actuators V2 controlling the clamp devices mounted on the trucks 26-29, the lines 59, 60 from valve D3 connect with the actuators V3 controlling the stationary clamp unit 56. Lines 176 and 177 from valve D4 connect with the actuator V4 controlling the vertical movements of printing roll 6; and the lines 191 and 192 from valve D5 connect with the actuator V5 controlling the longitudinal displacement of the racks 186 and 187 which determine the relative angular setting of the printing roll.

Camshaft 211 further carries a set of cams 231, 232 and 233 engaged by actuator plungers projecting from respective electric switch devices C1, C2, C3. Each switch device has connections leading in parallel to a power source, herein three-phase alternating source 246, and each switch device has a further pair of conductors connected therewith and leading to the energizing circuits of the respective electric motors or actuators earlier described. Specifically switch C1 is connected through lines 251 to motor M1 serving to reciprocate the movable inking rolls 87, 88, 89; switch C2 is connected by lines 252 with the motor M2 reciprocating the printing roll carriage 146; and switch C3 is connected by lines 253 with the electromagnetic actuators operating the conveyor belt drum brake devices 63 and 64.

Camshaft 211 further carries an indexing disk 258 which carries indicia, not shown, cooperating with a fixed marker 259 for indexing the various stages of an operating cycle, which cycle corresponds with one full revolution of the camshaft 211. Such operating cycle will now be described.

On termination of a preceding cycle of operation, the inking roll drive motor M is operating as is also the sequencing camshaft drive motor M3, while motors M1 and M2 are deenergized. The movable inking rolls 87, 88, 89 are positioned at the left hand end of their reciprocatory stroke, as shown in dotted lines in FIG. 8, in engagement with the surfaces of stationary inking rolls 76 and 77. The printing roll 6 is raised above the surface of the work. The brakes 63 and 64 of the conveyor drums are applied. The trucks 26, 27, 28, 29 are in their leftward or retracted position shown in FIG. 4, and their clamping devices are engaged to clamp the upper flight of belt 1 and the work 10. The stationary clamping unit 56 is also applied at this time. The racks 186 and 187 are positioned at the right-most end of their displacement as shown in FIG. 14c.

As the camshaft 211 commences a fresh revolution, it operates the actuator plungers of hydraulic valves D1-D5 and switches C1-C3 to produce the following sequence of events:

60 Valve D3 is actuated to supply pressure liquid through line 60 to actuator V3 so as to release the stationary clamp member 56 (FIG. 4).

65 Switch C3 is actuated to deenergize the electromagnetic actuator for releasing the drum brakes 63, 64 (FIG. 5).

Valve D1 is actuated to supply pressure liquid through line 54 to actuator V1 to displace the actuator piston to the right (FIG. 4). The conveyor belt 1 is therefore drawn by the clamping trucks 26-29 to effect one step of advance.

70 Switch C1 energizes motor M1 through lines 251 in a sense to impart rightward movement to the carriage 92 carrying the inking rolls 87-88 (see FIGS. 8 and 9). The said rolls loaded with ink from their previous engagement with the stationary inking rolls 76, 77, now assume

the positions shown in full lines in FIGS. 8 and 9 and deposit ink onto the surface of pattern plate 4.

As the conveyor belt 1 reaches the end of its step with stop 41 engaging the fixed abutment 43, valve D3 is actuated by its associated cam to supply pressure oil through 59 to the stationary clamp 56 to engage said clamp about the upper leaf of the conveyor belt and work; substantially simultaneously switch C3 operates the electromagnetically actuated brakes 63 and 64 to their applied condition; the work is thus arrested in position to receive a fresh print.

Valve D2 is actuated to supply oil via line 51 to the actuators V2, opening the clamp devices of trucks 26-29. Valve D1 is actuated to supply pressure oil via line 55 to actuator V1, causing the trucks 26-29 to recede leftward.

During this receding movement of the trucks switch C1 is actuated to impart a further leftward movement to the inking-roll-supporting carriage 92 (FIGS. 8 and 9), returning rolls 87-89 to the positions shown at 87a, 88a, 89a (FIG. 8) where they engage the stationary inking rolls 76 and 77. Also substantially concurrently switch C2 is actuated to energize motor M2 so as to displace the printing roll supporting carriage 146 from the position shown in FIGS. 3 and 14c where it overlies the work, to the position shown in FIG. 14a overlying the pattern plate 4. Throughout its displacement the printing roll is retained in its raised position out of engagement with either the work or the printing plate by the action of actuator V1 supplied with pressure oil through line 176 from valve D4.

As the printing roll 6 reaches the full-line position shown in FIG. 14a however, valve D4 now supplies oil to actuator V4 through line 177 to lower the printing roll into contact with the surface of block 4. Switch C2 is actuated to reverse the rotation of the motor M2 which thereupon moves the printing roll carriage 146 rightward (FIGS. 11 and 14a) while the printing roll 6 moves in frictionless rolling engagement with the surface of block 4 from the full-line position to the dotted-line position shown at 6a.

The width of the pattern plate or block 4 substantially equals the developed peripheral length of the printing roll and equals the width of the material 10 to be printed on. The relative setting of the roll 6 as later explained, is such that a longitudinal axial groove 20 provided on the printing roll is presented substantially in register with each of the side edges of the block 4, and each of the side selvedges of the work material thereby to ensure proper engagement and disengagement of the roll with and from the block, and a proper printing of the pattern on the work.

The carriage 146 supporting the printing roll proceeds on its course towards the work, and on reaching the work selvedge, substantially in the full line position 6b of FIG. 14b, the groove 20 is still positioned in register with the selvedge, as will presently appear. The printing roll therefore engages the work cleanly and accurately; moreover the groove 20 ensures that the roll will clear any selvedge clamps or pins that may be used in attaching the work to the conveyor belt. Thereafter the printing roll rolls in a frictionless, slipfree manner over the surface of the work and transfers thereto the pattern formed by the ink taken up by the roll from the pattern plate. As the roll 6 reaches the end of its stroke at 6c (FIG. 14c), after having completed nearly one full revolution in contact with the work, switch C2 is actuated by its cam to deenergize the motor M2, and valve D4 is actuated by its cam to operate actuator V4 to raise the printing roll. The cycle is now completed.

The reason for the reciprocation of racks 186 and 187 is the following. If the distance between the adjacent side edges of the pattern block 4 and the work 10 could be made strictly equal to the circumferential length of the printing roll 6, the racks could be made stationary. How-

ever, it is convenient to place the block 4 at a shorter distance from the work conveyor in order to reduce the lateral dimensions of the machine, and in any case accurate dimensioning would be difficult to maintain. This difficulty is overcome by the provision of the sliding rack arrangement described. The length of longitudinal travel of the racks is made equal to the distance E between the adjacent edges of plate or block 4 and the work 10. If such distance is greater than one half the developed length πD of the printing roll circumference (D being the roll diameter), then the length of displacement of the racks can be, and preferably is, reduced from the value E to the value $\pi D - E$. The result will be exactly the same, with the rotation of the roll being simply foreshortened by one complete revolution.

With the arrangement described, when the racks are displaced by their actuators V5 (controlled by the cam-actuated valve device D5) by the amount specified above, then the roll on reaching the selvedge of the work (position 6b) will be at exactly the same angular setting relative to the work selvedge as the relative angular setting of the roll relative to the edge of plate 4 at the time the roll first started moving away from said plate. The racks are then returned from the positions shown in FIG. 14c to their position shown in FIG. 14a during the return displacement of the printing roll towards the plate, and preferably while the roll is moving over the gap between the work and block 4.

In the polychrome printing press shown, it will be understood that all of the individual colour printing units (four in the example shown) are constructed as described above for unit 21, and all the units are operated in synchronism. A common sequencing control unit of the kind shown in FIG. 15 may be used for controlling the synchronous operation.

It is apparent that between adjacent printing units ample room can be made available for mounting any desired drying, curing and/or other processing appliances, such as blowers, radiating heaters and the like. It may be indicated in this connection that in a printing process according to the invention substantially less ink need be deposited on the work than in comparable dry offset printing processes of conventional type, e.g. using printing frames, so that correspondingly less drying or curing is required to set the prints.

Various modifications may be conceived and departures made from the details of the machine shown and described without departing from the scope of the invention. As one example, the double-acting fluid actuator V4 operating the up-and-down displacements of the printing roll may be replaced with a single-acting device in case the weight of the said roll with its associated parts is great enough to permit of substituting gravity for fluid pressure as the downward force acting on the printing roll. However, if a double-acting cylinder V4 is used as in the embodiment here described, the said actuator should be so dimensioned and the fluid pressure so selected as to ensure obtaining the proper pressure of the printing roll upon the work suitable for each particular printing operation. As a general rule, large-pattern prints would involve the use of higher pressures while finer and more delicate patterns will require lower pressure.

The amount of ink collected at the surface of the movable inking cylinders 87, 88, 89 depends on the time such cylinders dwell in contact with the stationary ink transfer cylinders 76, 77. It is, accordingly, desirable to provide some means of adjusting such dwell time, and this can be done by means of any suitable timing device of conventional character; conveniently the dwell time may be adjusted within a range of from one to four seconds or so. The possibility of thus adjusting the ink transfer time constitutes a distinct advantage over rotary textile printing machines of the conventional type in which the only way of controlling the quantity of ink deposited at each printing operation is by adjusting the doctor blade of

the ink store and/or the operating rate of the swinging ink transfer roll corresponding to roll 73 of the present drawings. If desired, moreover, the amount of ink transfer can be increased by a provision for double transfer.

While the invention has been described with reference to a textile printing process, it is to be understood that its teachings are applicable to printing processes on carriers other than textiles, e.g. paper, plastics, including rigid sheet materials such as metal sheet. The invention is applicable to type printing. In such an application (and in other applications), the pattern plate 4 of the described embodiment would be replaced by a smooth plate and the printing roll 6 made to carry a cylindrical type block (or pattern block) with raised type thereon.

In the specification and claims, the word ink (and its derivatives) is to be construed as including any transferable printing medium or agent.

What I claim is:

1. A printing machine comprising means for supporting a length of sheet material; means for intermittently advancing the supporting means in a longitudinal direction; a plate member having a generally flat pattern surface stationarily supported to one side of said material and substantially in a common plane therewith, inking means including a movable inking roll for supplying ink to said plate surface; said inking roll being movable across said plate member in a direction parallel to said longitudinal direction, an ink transfer member movable in a transverse direction from a position engaging said plate member to take up ink therefrom and into engagement with said sheet material to transfer said ink thereto; and means operable in timed relationship with said advancing means for moving said inking roll and said transfer member so as to ink said plate member and transfer ink from said plate member to said material in accordance with said pattern during a stationary period of said material supporting means.

2. In a printing machine, the combination comprising work supporting means providing a flat work surface; a flat plate member spaced from said work surface and substantially coplanar therewith; means supplying ink to said plate member; a roll member adapted to take up ink selectively from said plate member in accordance with a pattern and transfer said ink to said work surface; and means for supporting and displacing said roll comprising: a carriage supported for movement from said plate to said work and back; means supporting said roll from said carriage and movable between an operative position in which a generatrix of the roll lies on the common plane

of the plate and work surfaces for transferring ink from the former to the latter, and a retracted position; a rack parallel to the path of movement of the carriage; a gear journailed on the carriage and meshing with the rack; power means for rotating said gear; a second gear secured coaxially with the roll and having an outer radius substantially smaller than that of the roll; and a gear train interconnecting both gears, the drive ratio of the gearing so predetermined that the roll when in said operative position is rotated in substantially frictionless, slipfree rolling engagement with said plate and work surfaces.

3. In the machine claimed in claim 2, means mounting the rack for longitudinal displacement; and means imparting to the rack a displacement corresponding to the distance between adjacent sides of said plate and work surfaces during movement of said carriage from the time the roll has disengaged one of said surfaces to the time the roll has engaged the other surface.

4. The machine claimed in claim 2, wherein said means supporting the roll from said carriage comprise a support structure having said roll journailed thereto about one axis and pivoted to said carriage about another axis for rotational movement of said support structure and roll about a pivot axis between said operative and inoperative positions; and wherein said gearing comprises a pair of gears rotatable coaxially about said pivot axis and respectively meshing with said first and second gears.

5. The machine claimed in claim 1, wherein said inking means comprise at least one stationary inking roll supported with its axis transverse to said longitudinal direction to one side of said supporting means; means supplying ink to said stationary roll and means for continuously rotating said stationary inking roll; and at least one movable inking roll supported with its axis parallel to that of said stationary inking roll; and means for displacing said movable inking roll in timed relationship with said advancing means between a position in engagement with said stationary inking roll to take up ink therefrom and into rolling engagement across said plate member for delivering ink thereto.
